UNITED STATES PATENT OFFICE.

EDWARD Y. MOORE, OF CLEVELAND, OHIO.

HOISTING MECHANISM.

1,260,243.

Specification of Letters Patent. Patented Mar. 19, 1918.

Original application filed March 2, 1917, Serial No. 151,883. Divided and this application filed May 21, 1917. Serial No. 169,847.

To all whom it may concern:

Be it known that I, EDWARD Y. MOORE, a citizen of the United States, residing at Cleveland, in the county of Cuyahoga and 5 State of Ohio, have invented a certain new and useful Improvement in Hoisting Mechanism, of which the following is a full, clear, and exact description, reference being had to the accompanying drawings.

10 My prior application No. 151,883, filed March 2, 1917, of which this is a division, shows a dual trolley hoist wherein two raising members are operated by a single power mechanism. The present application relates to the particular form of power mechanism shown for rotating the shaft, which carries a plurality of lift wheels. This power mechanism has the advantages of being 15 compact, reliable and efficient, giving comparatively slow rotations to the driven shaft when the driving hand wheel is operated, and effectively holding the load against running down. The invention is hereinafter more fully explained, in connection with the drawings, and the essential 20 characteristics are set out in the claims.

In the drawings Figure 1 is a side elevation of the hoisting mechanism of this invention, the driven shaft, which may carry 25 any number of lift wheels, and the support, being broken off. Fig. 2 is a horizontal central section of the power mechanism on a larger scale; Fig. 3 is a vertical central section of the power mechanism on the same 30 scale as Fig. 2; Figs. 4 and 5 are perspectives on a reduced scale of the front and rear frame plates of the power mechanism respectively; Figs. 6 and 7 are sectional elevations on the lines 6-6 and 7-7 respectively 35 on Fig. 2, each looking toward the intermediate frame plate of the hoist. Fig. 8 is a perspective view of one of the double eccentric shafts employed in the hoist.

As shown in Fig. 1, 10 indicates the supporting member of the hoisting mechanism, which is shown as a downwardly facing 40 horizontal channel beam equipped with a surmounting plate 11. 12 is a bearing block bolted to the under side of the channel beam. 45 20 indicates the power mechanism with which this invention is specifically concerned, which is shown as bolted to the under side of the plate 11. The power mechanism is equipped with a driving hand wheel 40, resulting, as hereinafter described, in slow 50 rotation of the driven shaft 50. This driven

shaft is connected by a suitable loose-play coupling 60 with a shaft 62 mounted in the bearing block 12 and carrying a lift wheel 64, over which extends a lift chain 65 leading to the lift hook 66.

I will now describe particularly the power mechanism, referring to the other figures of the drawing.

The power mechanism proper is mounted 65 on a vertical central frame plate 21 which has at its upper end horizontal lugs 23 and 24 lying against the under side of the plate 11 and securely bolted thereto. The plate 21 is recessed at its upper edge, as shown 70 at 25, to allow it to extend readily beneath the channel beam 10. The frame of the power mechanism includes, beside the central supporting plate 21, a front plate 26 and a rear plate 27 bolted to the central 75 plate. These plates 26 and 27 are of the general form shown in Figs. 4 and 5 respectively, being stiffened by webs and having flanges, 28 and 29 respectively, which abut correspondingly formed flanges on the 80 central frame plate. The central frame plate is provided with suitable bosses 30 and 31, and the front and rear plates have ears 32 and 33 abutting against the ends of these bosses respectively. The cap screws 35 and 85 36 passing through the ears into the bosses hold the structure together.

The driving shaft of the power mechanism is designated 42. It is mounted in the front frame member 26 and in the central 90 plate 21. This shaft is rotated preferably by the hand wheel 40 which is mounted on the shaft and connected with it in a manner hereinafter described. A chain, not shown, is adapted to rotate the hand wheel. 95

Mounted on the shaft 42 on the inner face of the front plate 26 is a spur gear 43. This gear meshes with two other spur gears 70 and 71, which are rigid on shafts 72 and 73. These shafts are journaled in the central plate 21 and also in the other side plate 27. Between the plates 21 and 27 the shafts 72 and 73 are provided each with two eccentrics designated respectively 75, 76 and 77, 78. The eccentrics 75 and 77 lie in the same direction and extend into circular openings in a yoke plate 80, which has internal teeth 81. Similarly, the eccentrics 76 and 78 extend in the same direction, which is opposite to the two other eccentrics, and 105 these eccentrics occupy circular openings in the yoke 82 which has internal teeth 83. 110

The two sets of internal teeth work on a driven spur gear 52, which is located within the openings of both yokes and mounted on the driven shaft 50, this shaft being journaled in the central frame plate 21 and the rear plate 27.

The result of the above construction is that, as the driving shaft 42 is rotated, the shafts 72 and 73 carrying the eccentrics, 10 are rotated, and the eccentrics give the two yokes circular translations, or gyrations, which cause their internal teeth to slowly carry around the driven wheel 52 and the driven shaft. It will be seen that the speed 15 of the driven shaft is dependent on the difference in the number of teeth between the spur gear 52 and the internal gears on the yokes. That is to say, for each cycle of movement of the yokes the driven shaft is 20 rotated such a portion of a complete rotation as the difference between the number of internal teeth on the yoke and the number of external teeth on the spur gear bears to the total number of teeth on the spur 25 gear. The rotation of the driven shaft, therefore, is comparatively slow in proportion to that of the driving shaft, and thus the power is correspondingly increased.

To prevent either yoke from abutting the 30 eccentrics appertaining to the other yoke, I form bosses or enlargements on the inner sides of the respective yokes. These enlargements are designated 85 and 86 respectively. They engage each other sufficiently 35 to prevent either yoke contacting with the eccentrics for the other yoke.

To allow the power mechanism to automatically hold its load and at the same time to operate rapidly in the direction corresponding to descent of the load, enabling 40 the load to run down freely when desired, I provide a ratchet device for the driving shaft controlled by a friction clutch between the hand wheel and shaft. The clutch 45 is active on the raising movement but is released by a relatively backward movement of the hand wheel to allow the shaft 42 to turn independently of the ratchet. Briefly, this mechanism consists of a cup 90 freely 50 rotatable on the shaft 42 and provided with ratchet teeth 91 on its periphery adapted to be engaged by a pawl 92 carried by the front plate 26. Within the cup are a number of friction disks 94 connected alternately 55 with the cup and shaft 42. That is to say, the first disk may be connected at its inner periphery with the shaft, and the next disk at its outer periphery with the cup, and so on. Bearing against the front 60 of these disks is a plate 95. Against this plate the rear face of the hand wheel hub bears. The forward end of this hub is formed with an incline 97 which bears against an inclined collar 98 rigidly, though 65 adjustably, secured to the shaft 42.

The inclines between the collar 98 and the hand wheel hub are in the direction to force the hand wheel toward the power mechanism when the hand wheel is turned in the raising direction. Such operation, therefore, 70 clamps the disks and locks the hand wheel to the ratchet cup. The teeth on this cup are in such direction that the cup may rotate freely under the pawl 92, in the raising direction of rotation. Accordingly, in 75 the raising direction the hand wheel, disks and cup, rotate as a unit, the ratchet teeth clicking idly under the pawl but being held thereby whenever the movement ceases.

To lower the load the hand wheel is 80 turned in the opposite direction and this allows it to play back from the clutch, freeing the disks so that the shaft turns independently of the ratchet cup, and the load runs down so long as the hand wheel is 85 kept in advance in rotation from that caused by the descending load. Whenever this advance ceases the load is automatically held by the friction clutch, ratchet and pawl.

Such power mechanism as described, comprising broadly a gyrating internally toothed yoke driven by an eccentric, and the arrangement of two of such yokes operating concurrently, and the arrangement of the clutch-controlled ratchet, are claimed 90 in prior patents of mine, namely: Nos. 757,333, of April 12, 1904; 794,997, of July 18, 1905; 946,253, of January 11, 1910. Such patents, however, show a lift wheel within 95 the hoist mechanism on a sleeve through 100 which the driving shaft extends. The present invention enables the lift wheel to be located at any desired point at the side of the frame of the power mechanism, and any number of lift wheels to be employed. 105 The power mechanism is consolidated into the minimum of space, resulting in a very compact and efficient machine for causing rapid rotations of the hand wheel to result 110 in slow rotations of the driven shaft.

Having thus described my invention, what I claim is:

1. In a hoisting mechanism, the combination of a frame comprising three vertical plates side by side connected together, a pair of aligned shafts both mounted in the intermediate plate and each extending through one of the side plates, a hand wheel on one of the shafts beyond the frame, a pair of individual shafts mounted in the intermediate plate and the other side plate, an eccentric on each individual shaft, a spur gear on the driven shaft in the space between the intermediate plate and the last mentioned side plate, a yoke in such space 115 having internal teeth engaging the spur gear and having the eccentrics mounted in it, the individual shafts extending through the intermediate plate to the space on the other side thereof, gears on said individual 120 shafts, a clutch controlled by a ratchet device, a cup rotatable on the shaft 42 and provided with ratchet teeth 91 on its periphery, a pawl 92 carried by the front plate 26, a pair of friction disks 94 connected alternately with the cup and shaft 42, a plate 95 bearing against the front of the disks, an inclined collar 98 rigidly secured to the shaft 42, an inclined hub 97 on the front end of the shaft 42, an inclined 125 incline 97 on the hub 97, a hand wheel hub 99, a hand wheel 100, a clutch 101, a ratchet 102, a pawl 103, a front plate 104, a side plate 105, an intermediate plate 106, a driven shaft 107, a spur gear 108, a yoke 109, an eccentric 110, an individual shaft 111, an eccentric 112, a clutch 113, a ratchet 114, a pawl 115, a front plate 116, a side plate 117, an intermediate plate 118, a driven shaft 119, a spur gear 120, a yoke 121, an eccentric 122, an eccentric 123, a clutch 124, a ratchet 125, a pawl 126, a front plate 127, a side plate 128, an intermediate plate 129, a driven shaft 130, a spur gear 131, a yoke 132, an eccentric 133, an eccentric 134, a clutch 135, a ratchet 136, a pawl 137, a front plate 138, a side plate 139, an intermediate plate 140, a driven shaft 141, a spur gear 142, a yoke 143, an eccentric 144, an eccentric 145, a clutch 146, a ratchet 147, a pawl 148, a front plate 149, a side plate 150, an intermediate plate 151, a driven shaft 152, a spur gear 153, a yoke 154, an eccentric 155, an eccentric 156, a clutch 157, a ratchet 158, a pawl 159, a front plate 160, a side plate 161, an intermediate plate 162, a driven shaft 163, a spur gear 164, a yoke 165, an eccentric 166, an eccentric 167, a clutch 168, a ratchet 169, a pawl 170, a front plate 171, a side plate 172, an intermediate plate 173, a driven shaft 174, a spur gear 175, a yoke 176, an eccentric 177, an eccentric 178, a clutch 179, a ratchet 180, a pawl 181, a front plate 182, a side plate 183, an intermediate plate 184, a driven shaft 185, a spur gear 186, a yoke 187, an eccentric 188, an eccentric 189, a clutch 190, a ratchet 191, a pawl 192, a front plate 193, a side plate 194, an intermediate plate 195, a driven shaft 196, a spur gear 197, a yoke 198, an eccentric 199, an eccentric 200, a clutch 201, a ratchet 202, a pawl 203, a front plate 204, a side plate 205, an intermediate plate 206, a driven shaft 207, a spur gear 208, a yoke 209, an eccentric 210, an eccentric 211, a clutch 212, a ratchet 213, a pawl 214, a front plate 215, a side plate 216, an intermediate plate 217, a driven shaft 218, a spur gear 219, a yoke 220, an eccentric 221, an eccentric 222, a clutch 223, a ratchet 224, a pawl 225, a front plate 226, a side plate 227, an intermediate plate 228, a driven shaft 229, a spur gear 230, a yoke 231, an eccentric 232, an eccentric 233, a clutch 234, a ratchet 235, a pawl 236, a front plate 237, a side plate 238, an intermediate plate 239, a driven shaft 240, a spur gear 241, a yoke 242, an eccentric 243, an eccentric 244, a clutch 245, a ratchet 246, a pawl 247, a front plate 248, a side plate 249, an intermediate plate 250, a driven shaft 251, a spur gear 252, a yoke 253, an eccentric 254, an eccentric 255, a clutch 256, a ratchet 257, a pawl 258, a front plate 259, a side plate 260, an intermediate plate 261, a driven shaft 262, a spur gear 263, a yoke 264, an eccentric 265, an eccentric 266, a clutch 267, a ratchet 268, a pawl 269, a front plate 270, a side plate 271, an intermediate plate 272, a driven shaft 273, a spur gear 274, a yoke 275, an eccentric 276, an eccentric 277, a clutch 278, a ratchet 279, a pawl 280, a front plate 281, a side plate 282, an intermediate plate 283, a driven shaft 284, a spur gear 285, a yoke 286, an eccentric 287, an eccentric 288, a clutch 289, a ratchet 290, a pawl 291, a front plate 292, a side plate 293, an intermediate plate 294, a driven shaft 295, a spur gear 296, a yoke 297, an eccentric 298, an eccentric 299, a clutch 300, a ratchet 301, a pawl 302, a front plate 303, a side plate 304, an intermediate plate 305, a driven shaft 306, a spur gear 307, a yoke 308, an eccentric 309, an eccentric 310, a clutch 311, a ratchet 312, a pawl 313, a front plate 314, a side plate 315, an intermediate plate 316, a driven shaft 317, a spur gear 318, a yoke 319, an eccentric 320, an eccentric 321, a clutch 322, a ratchet 323, a pawl 324, a front plate 325, a side plate 326, an intermediate plate 327, a driven shaft 328, a spur gear 329, a yoke 330, an eccentric 331, an eccentric 332, a clutch 333, a ratchet 334, a pawl 335, a front plate 336, a side plate 337, an intermediate plate 338, a driven shaft 339, a spur gear 340, a yoke 341, an eccentric 342, an eccentric 343, a clutch 344, a ratchet 345, a pawl 346, a front plate 347, a side plate 348, an intermediate plate 349, a driven shaft 350, a spur gear 351, a yoke 352, an eccentric 353, an eccentric 354, a clutch 355, a ratchet 356, a pawl 357, a front plate 358, a side plate 359, an intermediate plate 360, a driven shaft 361, a spur gear 362, a yoke 363, an eccentric 364, an eccentric 365, a clutch 366, a ratchet 367, a pawl 368, a front plate 369, a side plate 370, an intermediate plate 371, a driven shaft 372, a spur gear 373, a yoke 374, an eccentric 375, an eccentric 376, a clutch 377, a ratchet 378, a pawl 379, a front plate 380, a side plate 381, an intermediate plate 382, a driven shaft 383, a spur gear 384, a yoke 385, an eccentric 386, an eccentric 387, a clutch 388, a ratchet 389, a pawl 390, a front plate 391, a side plate 392, an intermediate plate 393, a driven shaft 394, a spur gear 395, a yoke 396, an eccentric 397, an eccentric 398, a clutch 399, a ratchet 400, a pawl 401, a front plate 402, a side plate 403, an intermediate plate 404, a driven shaft 405, a spur gear 406, a yoke 407, an eccentric 408, an eccentric 409, a clutch 410, a ratchet 411, a pawl 412, a front plate 413, a side plate 414, an intermediate plate 415, a driven shaft 416, a spur gear 417, a yoke 418, an eccentric 419, an eccentric 420, a clutch 421, a ratchet 422, a pawl 423, a front plate 424, a side plate 425, an intermediate plate 426, a driven shaft 427, a spur gear 428, a yoke 429, an eccentric 430, an eccentric 431, a clutch 432, a ratchet 433, a pawl 434, a front plate 435, a side plate 436, an intermediate plate 437, a driven shaft 438, a spur gear 439, a yoke 440, an eccentric 441, an eccentric 442, a clutch 443, a ratchet 444, a pawl 445, a front plate 446, a side plate 447, an intermediate plate 448, a driven shaft 449, a spur gear 450, a yoke 451, an eccentric 452, an eccentric 453, a clutch 454, a ratchet 455, a pawl 456, a front plate 457, a side plate 458, an intermediate plate 459, a driven shaft 460, a spur gear 461, a yoke 462, an eccentric 463, an eccentric 464, a clutch 465, a ratchet 466, a pawl 467, a front plate 468, a side plate 469, an intermediate plate 470, a driven shaft 471, a spur gear 472, a yoke 473, an eccentric 474, an eccentric 475, a clutch 476, a ratchet 477, a pawl 478, a front plate 479, a side plate 480, an intermediate plate 481, a driven shaft 482, a spur gear 483, a yoke 484, an eccentric 485, an eccentric 486, a clutch 487, a ratchet 488, a pawl 489, a front plate 490, a side plate 491, an intermediate plate 492, a driven shaft 493, a spur gear 494, a yoke 495, an eccentric 496, an eccentric 497, a clutch 498, a ratchet 499, a pawl 500, a front plate 501, a side plate 502, an intermediate plate 503, a driven shaft 504, a spur gear 505, a yoke 506, an eccentric 507, an eccentric 508, a clutch 509, a ratchet 510, a pawl 511, a front plate 512, a side plate 513, an intermediate plate 514, a driven shaft 515, a spur gear 516, a yoke 517, an eccentric 518, an eccentric 519, a clutch 520, a ratchet 521, a pawl 522, a front plate 523, a side plate 524, an intermediate plate 525, a driven shaft 526, a spur gear 527, a yoke 528, an eccentric 529, an eccentric 530, a clutch 531, a ratchet 532, a pawl 533, a front plate 534, a side plate 535, an intermediate plate 536, a driven shaft 537, a spur gear 538, a yoke 539, an eccentric 540, an eccentric 541, a clutch 542, a ratchet 543, a pawl 544, a front plate 545, a side plate 546, an intermediate plate 547, a driven shaft 548, a spur gear 549, a yoke 550, an eccentric 551, an eccentric 552, a clutch 553, a ratchet 554, a pawl 555, a front plate 556, a side plate 557, an intermediate plate 558, a driven shaft 559, a spur gear 560, a yoke 561, an eccentric 562, an eccentric 563, a clutch 564, a ratchet 565, a pawl 566, a front plate 567, a side plate 568, an intermediate plate 569, a driven shaft 570, a spur gear 571, a yoke 572, an eccentric 573, an eccentric 574, a clutch 575, a ratchet 576, a pawl 577, a front plate 578, a side plate 579, an intermediate plate 580, a driven shaft 581, a spur gear 582, a yoke 583, an eccentric 584, an eccentric 585, a clutch 586, a ratchet 587, a pawl 588, a front plate 589, a side plate 590, an intermediate plate 591, a driven shaft 592, a spur gear 593, a yoke 594, an eccentric 595, an eccentric 596, a clutch 597, a ratchet 598, a pawl 599, a front plate 600, a side plate 601, an intermediate plate 602, a driven shaft 603, a spur gear 604, a yoke 605, an eccentric 606, an eccentric 607, a clutch 608, a ratchet 609, a pawl 610, a front plate 611, a side plate 612, an intermediate plate 613, a driven shaft 614, a spur gear 615, a yoke 616, an eccentric 617, an eccentric 618, a clutch 619, a ratchet 620, a pawl 621, a front plate 622, a side plate 623, an intermediate plate 624, a driven shaft 625, a spur gear 626, a yoke 627, an eccentric 628, an eccentric 629, a clutch 630, a ratchet 631, a pawl 632, a front plate 633, a side plate 634, an intermediate plate 635, a driven shaft 636, a spur gear 637, a yoke 638, an eccentric 639, an eccentric 640, a clutch 641, a ratchet 642, a pawl 643, a front plate 644, a side plate 645, an intermediate plate 646, a driven shaft 647, a spur gear 648, a yoke 649, an eccentric 650, an eccentric 651, a clutch 652, a ratchet 653, a pawl 654, a front plate 655, a side plate 656, an intermediate plate 657, a driven shaft 658, a spur gear 659, a yoke 660, an eccentric 661, an eccentric 662, a clutch 663, a ratchet 664, a pawl 665, a front plate 666, a side plate 667, an intermediate plate 668, a driven shaft 669, a spur gear 670, a yoke 671, an eccentric 672, an eccentric 673, a clutch 674, a ratchet 675, a pawl 676, a front plate 677, a side plate 678, an intermediate plate 679, a driven shaft 680, a spur gear 681, a yoke 682, an eccentric 683, an eccentric 684, a clutch 685, a ratchet 686, a pawl 687, a front plate 688, a side plate 689, an intermediate plate 690, a driven shaft 691, a spur gear 692, a yoke 693, an eccentric 694, an eccentric 695, a clutch 696, a ratchet 697, a pawl 698, a front plate 699, a side plate 700, an intermediate plate 701, a driven shaft 702, a spur gear 703, a yoke 704, an eccentric 705, an eccentric 706, a clutch 707, a ratchet 708, a pawl 709, a front plate 710, a side plate 711, an intermediate plate 712, a driven shaft 713, a spur gear 714, a yoke 715, an eccentric 716, an eccentric 717, a clutch 718, a ratchet 719, a pawl 720, a front plate 721, a side plate 722, an intermediate plate 723, a driven shaft 724, a spur gear 725, a yoke 726, an eccentric 727, an eccentric 728, a clutch 729, a ratchet 730, a pawl 731, a front plate 732, a side plate 733, an intermediate plate 734, a driven shaft 735, a spur gear 736, a yoke 737, an eccentric 738, an eccentric 739, a clutch 740, a ratchet 741, a pawl 742, a front plate 743, a side plate 744, an intermediate plate 745, a driven shaft 746, a spur gear 747, a yoke 748, an eccentric 749, an eccentric 750, a clutch 751, a ratchet 752, a pawl 753, a front plate 754, a side plate 755, an intermediate plate 756, a driven shaft 757, a spur gear 758, a yoke 759, an eccentric 760, an eccentric 761, a clutch 762, a ratchet 763, a pawl 764, a front plate 765, a side plate 766, an intermediate plate 767, a driven shaft 768, a spur gear 769, a yoke 770, an eccentric 771, an eccentric 772, a clutch 773, a ratchet 774, a pawl 775, a front plate 776, a side plate 777, an intermediate plate 778, a driven shaft 779, a spur gear 780, a yoke 781, an eccentric 782, an eccentric 783, a clutch 784, a ratchet 785, a pawl 786, a front plate 787, a side plate 788, an intermediate plate 789, a driven shaft 790, a spur gear 791, a yoke 792, an eccentric 793, an eccentric 794, a clutch 795, a ratchet 796, a pawl 797, a front plate 798, a side plate 799, an intermediate plate 800, a driven shaft 801, a spur gear 802, a yoke 803, an eccentric 804, an eccentric 805, a clutch 806, a ratchet 807, a pawl 808, a front plate 809, a side plate 810, an intermediate plate 811, a driven shaft 812, a spur gear 813, a yoke 814, an eccentric 815, an eccentric 816, a clutch 817, a ratchet 818, a pawl 819, a front plate 820, a side plate 821, an intermediate plate 833, a driven shaft 834, a spur gear 835, a yoke 836, an eccentric 837, an eccentric 838, a clutch 839, a ratchet 840, a pawl 841, a front plate 842, a side plate 843, an intermediate plate 844, a driven shaft 845, a spur gear 846, a yoke 847, an eccentric 848, an eccentric 849, a clutch 850, a ratchet 851, a pawl 852, a front plate 853, a side plate 854, an intermediate plate 855, a driven shaft 856, a spur gear 857, a yoke 858, an eccentric 859, an eccentric 860, a clutch 861, a ratchet 862, a pawl 863, a front plate 864, a side plate 865, an intermediate plate 866, a driven shaft 867, a spur gear 868, a yoke 869, an eccentric 870, an eccentric 871, a clutch 872, a ratchet 873, a pawl 874, a front plate 875, a side plate 876, an intermediate plate 877, a driven shaft 878, a spur gear 879, a yoke 880, an eccentric 881, an eccentric 882, a clutch 883, a ratchet 884, a pawl 885, a front plate 886, a side plate 887, an intermediate plate 888, a driven shaft 889, a spur gear 890, a yoke 891, an eccentric 892, an eccentric 893, a clutch 894, a ratchet 895, a pawl 896, a front plate 897, a side plate 898, an intermediate plate 899, a driven shaft 900, a spur gear 901, a yoke 902, an eccentric 903, an eccentric 904, a clutch 905, a ratchet 906, a pawl 907, a front plate 908, a side plate 909, an intermediate plate 910, a driven shaft 911, a spur gear 912, a yoke 913, an eccentric 914, an eccentric 915, a clutch 916, a ratchet 917, a pawl 918, a front plate 919, a side plate 920, an intermediate plate 921, a driven shaft 922, a spur gear 923, a yoke 924, an eccentric 925, an eccentric 926, a clutch 927, a ratchet 928, a pawl 929, a front plate 930, a side plate 931, an intermediate plate 932, a driven shaft 933, a spur gear 934, a yoke 935, an eccentric 936, an eccentric 937, a clutch 938, a ratchet 939, a pawl 940, a front plate 941, a side plate 942, an intermediate plate 943, a driven shaft 944, a spur gear 945, a yoke 946, an eccentric 947, an eccentric 948, a clutch 949, a ratchet 950, a pawl 951, a front plate 952, a side plate 953, an intermediate plate 954, a driven shaft 955, a spur gear 956, a yoke 957, an eccentric 958, an eccentric 959, a clutch 960, a ratchet 961, a pawl 962, a front plate 963, a side plate 964, an intermediate plate 965, a driven shaft 966, a spur gear 967, a yoke 968, an eccentric 969, an eccentric 970, a clutch 971, a ratchet 972, a pawl 973, a front plate 974, a side plate 975, an intermediate plate 976, a driven shaft 977, a spur gear 978, a yoke 979, an eccentric 980, an eccentric 981, a clutch 982, a ratchet 983, a pawl 984, a front plate 985, a side plate 986, an intermediate plate 987, a driven shaft 988, a spur gear 989, a yoke 990, an eccentric 991, an eccentric 992, a clutch 993, a ratchet 994, a pawl 995, a front plate 996, a side plate 997, an intermediate plate 998, a driven shaft 999, a spur gear 1000, a yoke 1001, an eccentric 1002, an eccentric 1003, a clutch 1004, a ratchet 1005, a pawl 1006, a front plate 1007, a side plate 1008, an intermediate plate 1009, a driven shaft 1010, a spur gear 1011, a yoke 1012, an eccentric 1013, an eccentric 1014, a clutch 1015, a ratchet 1016, a pawl 1017, a front plate 1018, a side plate 1019, an intermediate plate 1020, a driven shaft 1021, a spur gear 1022, a yoke 1023, an eccentric 1024, an eccentric 1025, a clutch 1026, a ratchet 1027, a pawl 1028, a front plate 1029, a side plate 1030, an intermediate plate 1031, a driven shaft 1032, a spur gear 1033, a yoke 1034, an eccentric 1035, an eccentric 1036, a clutch 1037, a ratchet 1038, a pawl 1039, a front plate 1040, a side plate 1041, an intermediate plate 1042, a driven shaft 1043, a spur gear 1044, a yoke 1045, an eccentric 1046, an eccentric 1047, a clutch 1048, a ratchet 1049, a pawl 1050, a front plate 1051, a side plate 1052, an intermediate plate 1053, a driven shaft 1054, a spur gear 1055, a yoke 1056, an eccentric 1057, an eccentric 1058, a clutch 1059, a ratchet 1060, a pawl 1061, a front plate 1062, a side plate 1063, an intermediate plate 1064, a driven shaft 1065, a spur gear 1066, a yoke 1067, an eccentric 1068, an eccentric 1069, a clutch 1070, a ratchet 1071, a pawl 1072, a front plate 1073, a side plate 1074, an intermediate plate 1075, a driven shaft 1076, a spur gear 1077, a yoke 1078, an eccentric 1079, an eccentric 1080, a clutch 1081, a ratchet 1082, a pawl 1083, a front plate 1084, a side plate 1085, an intermediate plate 1086, a driven shaft 1087, a spur gear 1088, a yoke 1089, an eccentric 1090, an eccentric 1091, a clutch 1092, a ratchet 1093, a pawl 1094, a front plate 1095, a side plate 1096, an intermediate plate 1097, a driven shaft 1098, a spur gear 1099, a yoke 1100, an eccentric 1101, an eccentric 1102, a clutch 1103, a ratchet 1104, a pawl 1105, a front plate 1106, a side plate 1107, an intermediate plate 1108, a driven shaft 1109, a spur gear 1110, a yoke 1111, an eccentric 1112, an eccentric 1113, a clutch 1114, a ratchet 1115, a pawl 1116, a front plate 1117, a side plate 1118, an intermediate plate 1119, a driven shaft 1120, a spur gear 1121, a yoke 1122, an eccentric 1123, an eccentric 1124, a clutch 1125, a ratchet 1126, a pawl 1127, a front plate 1128, a side plate 1129, an intermediate plate 1130, a driven shaft 1131, a spur gear 1132, a yoke 1133, an eccentric 1134, an eccentric 1135, a clutch 1136, a ratchet 1137, a pawl 1138, a front plate 1139, a side plate 1140, an intermediate plate 1141, a driven shaft 1142, a spur gear 1143, a yoke 1144, an eccentric 1145, an eccentric 1146, a clutch 1147, a ratchet 1148, a pawl 1149, a front plate 1150, a side plate 1151, an intermediate plate 1152, a driven shaft 1153, a spur gear 1154, a yoke 1155, an eccentric 1156, an eccentric 1157, a clutch 1158, a ratchet 1159, a pawl 1160, a front plate 1161, a side plate 1162, an intermediate plate 1163, a driven shaft 1164, a spur gear 1165, a yoke 1166, an eccentric 1167, an eccentric 1168, a clutch 1169, a ratchet 1170, a pawl 1171, a front plate 1172, a side plate 1173, an intermediate plate 1174, a driven shaft 1175, a spur gear 1176, a yoke 1177, an eccentric 1178, an eccentric 1179, a clutch 1180, a ratchet 1181, a pawl 1182, a front plate 1183, a side plate 1184, an intermediate plate 1185, a driven shaft 1186, a spur gear 1187, a yoke 1188, an eccentric 1189, an eccentric 1190, a clutch 1191, a ratchet 1192, a pawl 1193, a front plate 1194, a side plate 1195, an intermediate plate 1196, a driven shaft 1197, a spur gear 1198, a yoke 1199, an eccentric 1200, an eccentric 1201, a clutch 1202, a ratchet 1203, a pawl 1204, a front plate 1205, a side plate 1206, an intermediate plate 1207, a driven shaft 1208, a spur gear 1209, a yoke 1210, an eccentric 1211, an eccentric 1212, a clutch 1213, a ratchet 1214, a pawl 1215, a front plate 1216, a side plate 1217, an intermediate plate 1218, a driven shaft 1219, a spur gear 1220, a yoke 1221, an eccentric 1222, an eccentric 1223, a clutch 1224, a ratchet 1225, a pawl 1226, a front plate 1227, a side plate 1228, an intermediate plate 1229, a driven shaft 1230, a spur gear 1231, a yoke 1232, an eccentric 1233, an eccentric 1234, a clutch 1235, a ratchet 1236, a pawl 1237, a front plate 1238, a side plate 1239, an intermediate plate 1240, a driven shaft 1241, a spur gear 1242, a yoke 1243, an eccentric 1244, an eccentric 1245, a clutch 1246, a ratchet 1247, a pawl 1248, a front plate 1249, a side plate 1250, an intermediate plate 1251, a driven shaft 1252, a spur gear 1253, a yoke 1254, an eccentric 1255, an eccentric 1256, a clutch 1257, a ratchet 1258, a pawl 1259, a front plate 1260, a side plate 1261, an intermediate plate 1262, a driven shaft 1263, a spur gear 1264, a yoke 1265, an eccentric 1266, an eccentric 1267, a clutch 1268, a ratchet 1269, a pawl 1270, a front plate 1271, a side plate 1272, an intermediate plate 1273, a driven shaft 1274, a spur gear 1275, a yoke 1276, an eccentric 1277, an eccentric 1278, a clutch 1279, a ratchet 1280, a pawl 1281, a front plate 1282, a side plate 1283, an intermediate plate 1284, a driven shaft 1285, a spur gear 1286, a yoke 1287, an eccentric 1288, an eccentric 1289, a clutch 1290, a ratchet 1291, a pawl 1292, a front plate 1293, a side plate 1294, an intermediate plate 1295, a driven shaft 1296, a spur gear 1297, a yoke 1298, an eccentric 1299, an eccentric 1300, a clutch 1301, a ratchet

shafts in such latter space, and a central gear on the driving shaft in such latter space meshing with the gears first mentioned.

2. The combination of a driving and a driven shaft, a gear on the driven shaft, a pair of internally-toothed yokes mounted side by side and surrounding said gear, a pair of shafts each provided with two eccentrics for gyrating said yokes, bosses on the adjacent faces of said yokes preventing either from engaging the eccentrics appertaining to the other, and gearing connecting the driving shaft with said eccentrics.

3. In a hoisting mechanism, the combination of a frame comprising three vertical plates side by side connected together, a pair of aligned shafts both mounted in the intermediate plate and each extending through one of the side plates, a pair of individual shafts mounted in the intermediate plate and one of the side plates, two eccentrics on each individual shaft, a spur gear on the driven shaft in the space between the intermediate plate and the last mentioned side plate, a pair of yokes in such space each having internal teeth engaging the spur gear and having the eccentrics mounted in it, the two yokes being provided on their adjacent sides with means for main-

taining them separated when they surround the eccentrics, gears on said individual shafts on the other side of the intermediate frame plate, and a central gear on the driving shaft meshing with the gears first mentioned.

4. In a hoisting mechanism, the combination of an intermediate frame plate having laterally extending supporting ears, a driving shaft on one side of the plate and journaled therein, a driven shaft on the other side of the plate journaled therein and in alignment with the driving shaft, a pair of individual shafts extending through said plate, gearing between the driving shaft and the individual shafts on one side of the plate, eccentrics on the individual shafts on the other side of the plate, an internally toothed yoke mounted on said eccentrics, a spur gear on the driven shaft lying within and engaged by the internal teeth of the yoke, and two frame plates carrying respectively the other bearings of the driving and driven shaft and bolted to said intermediate plate on opposite sides thereof.

In testimony whereof, I hereunto affix my signature.

EDWARD Y. MOORE.
